DUSTPROOF WATCHCASE WITH NONBREAKABLE CRYSTAL

Application filed March 24, 1927. Serial No. 177,855.

Our invention relates to watch cases generally but is more particularly designed to produce a dust-proof case for use in wrist watches and is specifically adapted to facilitate the use of a non-breakable crystal in such cases.

By "non-breakable crystals" we mean, those usually made of some easily moldable, slightly elastic, flexible, transparent material, such for instance as celluloid, compounds of urea or similar materials, although possibly crystals of this character and of the desired shape for use in our invention might be made of some form of tough glass.

15 The difficulties heretofore frequently encountered with non-breakable crystals on the market have comprised the liability of such crystals to get loose from the ordinary frame in which they have been set, partly on account of their flexibility and partly on account of their liability to contract and expand with the variations of temperature and moisture. Also, by reason of their substantially flat form they have been liable to be easily pressed 20 down upon the hands of the watch and interfere with its satisfactory operation. Moreover, cases for use with wrist watches provided with ordinary glass or special non-breakable crystals have not been as dust- 25 proof as is desirable in view of the exposure of such watches to dust and dirt. It has been the experience of the applicants that dust will enter the movement of a watch more readily through the front or crystal portion 30 of the casing than elsewhere and it is one of the primary purposes of this invention to minimize this, for the entrance of dust, moisture or the like into the watch movement is obviously most deleterious. We find that 35 with our invention we can utilize as a seal, to carry this inventive thought into effect, a crystal so formed that it acts as a dust and moisture excluding element, though the specific form of crystal disclosed herein constitutes only one embodiment of the invention.

Generally speaking, our invention overcomes all of these difficulties by employing a crystal having a fairly wide, downwardly extending border flange, perfectly combined 40 with a main body frame containing the watch

movement which is provided with a deep peripheral groove substantially at right angles to the face of the watch into which said flange may fit, whereby an efficient dust-proof joint is secured. Such construction is principally feasible with crystals of celluloid or similarly easily moldable material although it might be otherwise produced. 55

The best form of apparatus at present known to us embodying our invention is 60 illustrated in the accompanying sheet of drawings in which:

Fig. 1 is a perspective view of the main body of the case.

Fig. 2 is a perspective view of the preferred 65 form of crystal.

Fig. 3 is a perspective view of the preferred form of outer frame which also serves as a link in the wrist band.

Fig. 4 is a vertical, central section of the 70 assembled casing showing a watch movement therein, and

Fig. 5 is a perspective view upon a smaller scale of a completed watch showing a wrist band attached thereto. 75

Throughout the drawings like reference characters indicate like parts. 1 represents generally a watch movement having the hands 2, and 3 is the main body of the casing which is usually formed of a block of 80 metal having the cavity 13 in which the movement 1 may be set with its dial 18 extending over the face of such cavity. This frame body 3 has the deep peripheral slot or groove 4 formed in it. 5 represents the crystal having 85 the flange 6 of considerable width extending at right angles to the face of the crystal and adapted to nest in the slot 4 as shown in Fig. 4. Preferably the face of the crystal is joined to the flange 6 by some convenient form of bead 7 which raises the face of the crystal the desired distance above the dial 18 so as to cause it to clear the hands 2. 90

8 is the outer frame which, in the case of a wrist watch, is made with projecting ears 10 95 to which any convenient form of wrist band 11 may be attached. For simplicity sake this wrist band is shown in Fig. 5 as being continuous as though it were made of elastic material, although of course it could be made 100

of other materials in separate sections connected together by any adjustable fastening (not shown) in the usual way. The outer frame 8, whether made in the form of a link 5 for wrist watches or otherwise, is provided with a continuous inwardly extending lip 9 which overhangs and engages the periphery of the crystal 5, preferably engaging the peripheral depression in the bead 7, as shown 10 in Fig. 4.

14 represents the usual winding stem projecting from the watch movement through slots 12 in the body of the case, 12a in the crystal flange and 12b in the outer frame or link 8. Preferably a sleeve or washer of elastic material such as felt indicated at 15 in Fig. 5 may surround the stem 14 and fill the surrounding portions of the slots 12, 12a and 12b to prevent admission of dust through 20 the annular space which might otherwise be left between the stem and portions of the case immediately surrounding it.

Any convenient and usual means may be employed for detachably securing the parts 25 in the assembled position shown in Fig. 4, such for instance as the small shoulders or projections 16, 16 on the exterior of the body 3 of the case engaging corresponding slots or depressions 17, 17 in the inner surface of 30 the slightly elastic outer frame 8.

In operating the invention the watch movement 1 is set in the cavity 13 of the main body of the frame 3, the dial 18 placed over it, and the hands 2 placed in position, the 35 crystal 5 then placed over the dial with its flanges 6 extending to the bottom of slots 4 in the main body 3, and the outer frame 8 snapped down into position as shown in Fig. 4. In taking out the watch movement from 40 the case, the above operations are performed in reverse order.

The advantage of our invention comprise the firmness with which the crystal is gripped in the assembled casing so that it cannot possibly drop out or get loose; the perfect character of the dust-proof joint between crystal and case body produced by the cooperating action of the deep groove 4, in the case body, and the relatively wide flange 6 on the crystal; 50 the insurance of sufficient clearance for the hands 2 secured by the bead 7 without correspondingly increasing the thickness of the casing proper, and the increased rigidity given to the crystal by the use of said circumferential bead. This latter quality is particularly important because of the general flexibility of the material out of which non-breakable crystals are usually made.

While we have illustrated our invention as 55 applied to a watch of rectangular shape it is obvious that it could be similarly employed with watches of other shapes, and that it could be applied to watches other than wrist watches, both of the open face and hunting case type. Also various changes in the de-

tails of construction could be made without departing from the principle of our invention so long as the main feature of the engagement of a relatively wide flange on the crystal engaging the correspondingly deep slot in the 60 casing is retained.

Having described our invention, we claim:

1. A watch case comprising, in combination, a main body having a cavity for the reception of a watch movement and provided with a relatively deep peripheral slot, a crystal provided with a depending flange adapted to enter, and extend substantially to the bottom of, said slot, and means for holding said parts in assembled relation. 70

2. The combination in claim 1 in which said flange extends continuously around the periphery of said crystal, and is arranged at substantially right angles to the face thereof. 80

3. The combination in claim 1 in which said crystal is formed of a flexible material and is provided with a peripheral bead whereby the face of the crystal is stiffened and a portion of it spaced away from the main body of the casing frame. 85

4. The combination in claim 1 in which said main casing body and crystal flange are provided with registering slots through which the winding stem of the watch may project. 90

5. In a dust-proof watch, a casing, a watch movement therein, and a crystal of box-like form having a continuous, depending peripheral flange of relatively considerable width molded integrally with its face and extending substantially at right angles thereto and closely fitting around the sides of said casing to form a dust-proof joint therewith. 100

6. The combination found in claim 5 in which said crystal has a substantially flat face provided with a peripherally arranged slightly reentrant portion adapted to hold the area of the face of said crystal thereby surrounded slightly above and away from the upper surface of said watch movement. 105

7. The herein described dust-proof watch case having, in combination, a main body having a cavity for reception of a watch movement and a peripheral groove surrounding said cavity of substantially the same depth as said cavity, a crystal shaped like a box cover adapted to fit tightly into said groove, and a surrounding outer frame adapted to detachably engage said body and said crystal and hold the same in assembled relation with the crystal flange sunk in said groove. 115

8. A watch having, in combination a casing, a movement therein, a winding stem and a crystal, said casing and crystal being shaped respectively like the body and cover of a box, the casing having a deep peripheral groove into which the crystal fits, said casing and crystal having registering slots which, when 120

the parts are assembled, leave a small orifice through which said stem may project.

9. In a watch case the combination of a main body adapted to receive and hold a watch movement and provided on its face with an encircling marginal groove, the opposite walls of which groove extend substantially perpendicularly to the plane of the said face, a crystal provided with a continuous depending flange adapted to fit snugly in said groove when the parts are assembled, and means for holding said parts in assembled relation.

10. A watch having a dust-proof case comprising a back and sides, a watch movement therein, a watch crystal having its peripheral edge turned down and extending on a plurality of its sides to approximately the depth of the casing sides and frictionally fitting the same, and a winding stem projecting through said case.

11. As an element in a dust proof watch case embodying the construction herein described, a watch case body in the form of a shallow receptacle adapted to receive and hold a watch movement and provided with a narrow, peripheral groove surrounding the movement-holding space therein, said groove being of uniform width throughout and of a depth several times its width; whereby, when a crystal having a continuous, peripheral, right-angled flange adapted to fit snugly in said groove has such flange nested therein, a dust proof enclosure for the contained watch movement is thereby produced.

12. In a watch, the combination of a watch crystal having a flange which is perpendicular with respect to a plane at right angles to the principal axis of the crystal around its periphery and a watch case adapted to carry said crystal, in which the bezel of said case engages the front of said crystal and the depending flange extends into the case centre and around the watch movement.

13. In a watch, the combination of a watch crystal having a flange which is perpendicular with respect to a plane at right angles to the principal axis of the crystal around its periphery, a step around the crystal face, and a watch case adapted to carry said crystal, in which the bezel of said case engages the front of said crystal and the depending flange extends into the case centre and around the watch movement.

14. In a watch, the combination of a watch crystal having a flange which is perpendicular with respect to a plane at right angles to the principal axis of the crystal around its periphery, and a watch case in which the bezel engages the front of said crystal, and the back of said case engages the depending flange of the crystal to form a joint between the casing and the crystal.
